Primary Examiner — Susan Moon Lee(74) *Attorney, Agent, or Firm* — Price Heneveld LLP(57) **CLAIM**

I claim the ornamental design for a portable hanging animal feeder, as shown and described.

DESCRIPTION

FIG. 1 is a side elevation view of a portable hanging animal feeder; the other sides being substantially identical;

FIG. 2 is a top view thereof; and,

FIG. 3 is a bottom view thereof.

Broken lines and unshaded portions contained within broken lines are not claimed.
